UNITED STATES PATENT OFFICE.

IRA A. SHANTON, OF ST. PETERSBURG, FLORIDA.

SPRING TEETERING TOY.

Application filed December 24, 1925. Serial No. 77,504.

My invention relates generally to toys and more particularly to a spring teetering toy or plaything that is designed to afford pleasing, beneficial and interesting amusement for children, and at the same time to provide an attractive form of mild exercise for the users of the toy.

The principal objects of my invention are to generally improve upon and simplify the existing forms of spring teetering toys; to provide a toy of the character referred to that is relatively simple in construction, capable of being easily and cheaply produced, further, to provide simple and efficient means for regulating the tension of the spring that supports the user of the toy, thereby enabling the toy to be used by children of different weights, and further, to produce a toy that involves the dual principles of both teetering and rocking motions, thereby simulating the pleasing effects produced by horseback riding.

In practically all of the spring teetering toys now on the market, no provision is made for regulating the tension of the spring, and thus the toy may only be used successfully by children of a given weight or within a relatively narrow range or limit of weights.

I propose to overcome this disadvantage and increase the usefulness of the amusement device, by providing the spring arm of the toy with auxiliary means, preferably a spring or springs that will be effective in increasing the tension or resiliency of the main spring arm, thereby enabling the toy to be effectively and conveniently used by children of different weights.

A further object of my invention is to provide a spring teetering toy with a saddle-like seat that is mounted for limited rocking movement, thereby imparting to the child or occupant of the seat the effect of riding a pony or horse and which result, it will be understood, materially enhances the attractiveness and utility of the toy.

With the foregoing and other objects in view, my invention consists in certain novel features of construction and arrangement of parts that will be hereinafter more fully described and claimed and illustrated in the accompanying drawings in which:

Fig. 1 is a side elevational view of a spring teetering toy constructed in accordance with my invention.

Fig. 2 is an enlarged vertical section taken on the line 2—2 of Fig. 1.

Fig. 3 is an enlarged cross section taken on the line 3—3 of Fig. 1.

Fig. 4 is a plan view of the toy.

Fig. 5 is an enlarged cross section taken on the line 5—5 of Fig. 1.

Referring by numerals to the accompanying drawings which illustrate a practical embodiment of my invention, 10 designates a base member, preferably a flat board or panel and secured on top of one end thereof is a block 11 having an inclined upper face and which functions as a fulcrum for the swinging arm of the toy.

Mounted in any suitable manner on block 11 and lying on the inclined face thereof is the lower portion of a spring arm 12, preferably formed of steel and having a relatively high degree of resiliency. This spring arm normally occupies an angular position of about 30 or 35 degrees relative to a horizontal plane.

Adjustably secured in any suitable manner to the upper portion of the spring arm 12 is a bracket 13 and pivotally connected or hinged thereto so as to rock on a horizontal axis 14 is a saddle-like seat 15, that is adapted to be occupied by the user of the toy. This bracket may be adjustably secured to arm 12 in various ways, but I prefer to lock said bracket to said arm by means of a wedge member 13^a that is driven between said bracket and one edge of said arm (see Fig. 3).

Secured to spring arm 12 a short distance in front of bracket 13 is one end of a spring 16, the free end of which bears against the underside of seat 15 in front of axis 14.

Thus, the rear portion of the seat normally bears on top of the rear portion of the spring arm.

Secured to and projecting upwardly from the front portion of the seat is a panel 17 that is shaped and painted so as to represent the head and neck of a pony and projecting outwardly from the sides of this panel are short rods 18 that serve as handles to be grasped by the occupant of seat 15.

A foot rest 19 is provided by bending a loop 20 in the central portion of a metal strap or bar, which loop receives the spring arm 12 and to lock this foot rest to the arm, a wedge or key 21 is driven between the edge

of the arm and one end of loop 20 (see Fig. 5).

An integral portion of spring arm 12 at its lower forward end is bent upwardly in goose-neck form to provide a relatively short upstanding spring arm 22 and arranged on the upper portion of this short spring arm is a plurality of rings or loops 23.

Inasmuch as this arm 22 is a continuation of arm 12, it has a certain degree of resiliency, but on account of its short length, it offers considerable resistance to flexing forces.

In order to increase the tension of spring arm 12 so that it will flex properly while the toy is being used by heavier children, a flexible member 24 such as a cord, rope, chain or wire connects the upper portion of the short arm 22 with the intermediate or upper portion of spring arm 12. This flexible connection may include a suitable retractile coil spring such as 25 and its forward end may be connected to any one of the loops 23, thereby taking advantage of different degrees of resiliency of the short spring arm 22.

The rear or upper end of this flexible connection may be connected at any desired point throughout the length of spring arm 12 in order to obtain the proper tension or resistance to flexure when the toy is used by children of varying weights. The upper or rear end of flexible member 24 may be detachably connected to the central portion of the adjustable foot rest 19 as shown by solid lines in Fig. 1, or it may be connected to a separate loop or bracket that is adjustably mounted on spring arm 12, as shown by dotted lines in Fig. 1.

Obviously the flexible member must be constructed so that it may be easily and quickly applied to or removed from the long and short spring arms.

In some instances the spring 16 that bears against the underside of the seat 15 may be dispensed with and an ordinary spring hinge used as a connection between the spring arm 12 and the seat.

When the toy is used by a comparatively small or light weight child, the flexible connection between the short and long springs is dispensed with, but when a larger and heavier child desires to use the toy, the flexible member is installed, thereby providing the required increase in tension or resistance to flexure and thus the usefulness of the toy is materially increased in that it may be used by children whose weights vary from thirty to forty pounds up to one hundred 60 pounds or over.

In the use of the toy, the child is placed on seat 15 with the feet on rest 19, and the hands grasping rods 18.

A slight movement of the body will cause 65 spring arm 12 to flex or teeter vertically

on block 11 as a fulcrum and simultaneously with this teetering movement, the seat will rock on its axis 14, thereby producing the pleasing and beneficial effects that simulate the riding of a horse or pony.

It will be understood that minor changes in the size, form and construction of the various parts of my improved spring teetering toy may be made and substituted for those herein shown and described without departing from the spirit of the invention, the scope of which is set forth in the appended claims.

I claim as my invention:

1. In a spring teetering toy the combination with a base, of a spring arm mounted on said base and extending upwardly at an angle relative thereto, a seat carried by the free end of said spring arm, a relatively short spring arm projecting upwardly from the lower end of the first mentioned spring arm and a flexible connection between said relatively short spring arm and the upper portion of the angularly disposed spring arm.

2. A spring teetering toy comprising a base, a spring arm mounted on said base and projecting upwardly at an angle therefrom, a seat mounted for rocking movement on the upper portion of said spring arm the lower end of which spring arm is bent upwardly to provide a relatively short auxiliary spring arm and a flexible member adjustably connected to the upper portion of the auxiliary spring arm and the intermediate portion of the angularly disposed spring arm.

3. A spring teetering toy comprising a base, a spring arm mounted on said base and projecting upwardly at an angle therefrom, a seat mounted on the upper portion of said spring arm, the lower end of said spring arm being bent upwardly to provide a relatively short auxiliary spring arm, and a flexible connection between said auxiliary spring arm and the upper portion of the inclined spring arm.

4. In a spring teetering toy, a base, a fulcrum block mounted adjacent to one end of said base, a section of resilient material mounted on said fulcrum block at a point intermediate the ends of said section of resilient material to form a main spring arm that occupies an inclined position relative to said base and a short spring arm that occupies a substantially vertical position relative to said base, a member connecting the upper portion of the short spring arm with the intermediate portion of the long spring arm and a seat carried by the upper portion of the long spring arm.

5. In a spring teetering toy, a base, a fulcrum block mounted adjacent to one end of said base, a section of resilient material mounted on said fulcrum block at a point

intermediate the ends of said section of resilient material to form a main spring arm that occupies an inclined position relative to said base and a short spring arm that occupies a substantially vertical position relative to said base, a member connecting the upper portion of the short spring arm with the intermediate portion of the long spring arm, a seat carried by the upper portion of the long spring arm and an adjustable foot rest arranged on the long spring arm in front of said seat.

6. In a spring teetering toy, a base, an inclined arm having its lower end fulcrumed on said base so as to swing through a vertical plane, a seat carried by the upper portion of said swinging arm, a short resilient member projecting upwardly from the base adjacent to the lower end of the swinging arm and an adjustable connection between the upper portion of said vertically disposed

arm and the intermediate portion of the swinging arm for varying the resistance of said inclined arm to swinging movements.

7. In a spring teetering toy, a base, a fulcrum block mounted thereon, which fulcrum block is provided with an inclined upper face, an inclined arm having its lower portion mounted on the inclined face of said fulcrum block so that said arm occupies an inclined position relative to the base, a seat carried by the upper portion of said swinging arm, a short arm projecting upwardly from the base adjacent to said fulcrum block and a flexible connection between the upper portion of said short arm and the intermediate portion of the swinging arm for yieldingly resisting the downward swinging movements of said inclined arm.

In testimony whereof I affix my signature.

IRA A. SHANTON.
